UNITED STATES PATENT OFFICE.

JOHN A. HAGERSTROM, OF SCRANTON, PENNSYLVANIA, ASSIGNOR TO TECHNICAL SUPPLY COMPANY, OF SCRANTON, PENNSYLVANIA, A CORPORATION OF NEW JERSEY.

MATHEMATICAL INSTRUMENT AND THE LIKE.

1,309,131.

Specification of Letters Patent.

Patented July 8, 1919.

Application filed May 31, 1918. Serial No. 237,519.

To all whom it may concern:

Be it known that I, JOHN A. HAGERSTROM, a citizen of the United States, and a resident of the city of Scranton, in the county 5 of Lackawanna and State of Pennsylvania, have invented certain new and useful Improvements in Mathematical Instruments and the like, of which the following is a specification.

10 The present invention relates to the manufacture of that class of manual implements which are technically called instruments of precision or mathematical instruments, including compasses, dividers, calipers, and 15 other tools specially adapted for measuring, drawing, or delineating various objects, or representations thereof, either for commercial, or scientific, or artistic purposes.

One of the objects of the invention is to 20 produce an instrument of the class mentioned having a practically perfect joint, which can be made easily and expeditiously from plain material, as ordinarily found in stock, and will require but a few simple operations to evolve its component parts and 25 assemble them together.

A further object is the production, in an instrument of the type described, of a secure and smooth-working joint consisting of the 30 minimum number of elements necessary to supply that essential characteristic of a meritorious article of the nature set forth.

A general object is to provide a joint for an instrument of the kind referred to, which 35 shall be of strong and durable construction, not susceptible of derangement through ordinary usage, readily disassembled for inspection or repairs, and economical to manufacture.

40 Other objects and advantages of the invention will become apparent as the specification proceeds.

A convenient and satisfactory form of instrument joint, embodying the invention 45 disclosed herein, is illustrated by way of example in the accompanying drawings, wherein:—

Figure I is a side elevation, drawn to an enlarged scale, of the upper part of an instrument in which this improved joint is 50 incorporated;

Fig. II is a central longitudinal section of the same part of the instrument, viewed at right angles to the position shown in the 55 preceding figure;

Fig. III is a fragmentary side view showing an appropriate form of material or stock from which the hinge members of the instrument are principally made;

Fig. IV shows the same material in transverse section, that is, in its original shape;

Fig. V is a side elevation illustrating the shape assumed by the material after the initial operations for producing the joint have been performed thereon;

Fig. VI is an oblique section on the line VI—VI of Fig. V, looking at the sectioned part exclusively, in the direction pointed out by the arrows, that is, upwardly to the right;

Fig. VII is a side elevation representing the material, previously operated upon as in Fig. V, now formed with a loop at one end to constitute one of the said hinge members, the loop surrounding a bearing element set 75 therein for the pivot of the joint;

Fig. VIII is a cross-section on the line VIII—VIII of Fig. V, looking in either direction;

Fig. IX is a section along the oblique line IX—IX of Fig. VII, looking downwardly to the right, as pointed out by the arrows in the latter-named figure;

Fig. X is a detached view, in side elevation, of the bearing element shown within 85 the loop in Fig. VII;

Fig. XI is an edge view of the same element, again detached;

Fig. XII is an edge view of the complete hinge member represented in side elevation 90 by Fig. VII; and

Fig. XIII is a section showing the material as if severed across the right end of Fig. XII, being of same form as appears in Fig. IV, but differently positioned.

As indicated in Fig. I, the instrument to which the improved joint is applied usually has two legs or members A and B. Due to the peculiar formation of the joint, herein-after described, these members need not be 100 made of broad or heavy material, such as ordinarily is resorted to in order to allow for deep cutting in the process of forming the old type of joint, and subsequently is tooled down and provided with lateral depressions to eliminate surplus material and lighten the instrument to some extent. In carrying out the present invention, it is not required to use any but relatively thin material, for instance, light bar metal, and which 110

can be formed by drawing, rolling, or milling to the desired section. A simple and useful form as well is shown in the drawing, the same having flat, parallel sides 1 and 2, and 5 rounded or curved edges 3 and 4, best seen in cross-section, Figs. IV and XIII.

The first step in preparing the said members A and B, to adapt the same as hinge members to be joined together, is to produce 10 at one end of each a reduced or milled-down portion, denoted by the reference numerals 7, 8, and 9, in Fig. V. As represented, this reduced portion includes an elongate level surface 8 and curved terminals 7 and 9. 15 The latter are formed according to certain radii, hereinafter described. Beyond the terminal, 7, the end of each member is cut to a predetermined angle to produce in addition an acutely-beveled portion 10, which is 20 made concave or inwardly rounded, as at 11, Fig. VI, to conform to the curvature of the edge 3, previously mentioned.

Being prepared in the manner above expressed, the said reduced portion of each 25 member A, B, is then turned around over a mandrel, or equivalent contrivance, so that the elongate surface and the terminals thereof, before spoken of, become adjoining arcs of a circle, as indicated by the reference 30 characters 7^a, 8^a, and 9^a, in Fig. VII, and form together a circular loop, designated as a whole by the reference letter C.

Within each of the loops C is placed a 35 collar or centrally apertured disk 14, which is brazed therein and designed to afford a bearing in its respective member, A or B, for the hinge pivot, hereinafter described in detail. Preferably, and as shown in Figs. 40 II and IX, the said collar, or disk or bearing, is located flush with the outer face of its member.

The loop C is next milled or thinned down on one side, as at 12, approximately to one-half the original thickness of the material 45 composing the members A, B, taken flatwise. This thinned-down portion 12 of the loop is bounded inwardly by an overhanging ledge 13, formed obliquely across the material in each member, on the flat side thereof indicated by the numeral 2.

The collar 14 is made of less width, measured edgewise, than that of the thinned-down loop C, whereby a recess 15 is left in each loop, with a flat surface 16, encircling 55 the same, so that when two such loops are conjoined facing each other as illustrated, there remains a vacant space therewithin which precludes any contact of the oppositely-located collars, disks, or bearings, and 60 further confines the necessary frictional adherence of the hinge members solely to the peripheries of their said loops, intermediate of the contacting surface.

It will be noted that the radius of the collar, disk, or bearing 14 illustrated by Fig.

X corresponds to the radii of the terminals 7 and 9 of the reduced portion of each hinge member, first hereinabove described and shown to best advantage in Fig. V, which terminals meet at the inner extremity of the 70 beveled end portion 10, when the loop C is being formed. Then the rounded edge 3 of the hinge member and the inwardly curved face of the said beveled portion 10 adjoin each other, as clearly indicated in Fig. VII. 75

The oppositely-located collars, disks, or bearings 14, referred to above, have each a central opening 17, which is countersunk on the outside, that is, made flaring outwardly, as at 18, Fig. IX. These openings and 80 countersinks or concavities become aligned through the apposition of the loops pertaining to the members A, B, as shown in Fig. III, and form across them a continuous passage for a pivot to hinge the same one to 85 the other.

Over the hinge end of the members A, B is placed a bifurcated support 19, the branches of which terminate in a pair of annuli 20 and 21, located exteriorly in relation to the outer faces of the conjoined loops of the said members and concentric therewith. The annuli, it will be seen by reference to Fig. II, are similarly concentric with the bearings 14, and their aligned openings 17 and concavities 18. A conical protuberance 22 is formed by projecting the inner edge or margin of the annulus 20, and this is received in the concavity of the adjacent bearing 14. The inner edge or margin of the annulus 21, on the other hand, is not deflected, but is threaded to receive a corresponding thread 23, provided around the outer part of a conical head or enlargement 24, of a pivot-screw 25. The tapering portion of the head or enlargement 24 fits the concavity in the other bearing 14. The central openings 17 in the opposed bearings enable them to be journaled on a smooth-surfaced intermediate portion of the pivot-screw, while their outwardly-disposed concavities 18 are respectively engaged by the conical protuberance 22 and the similarly-shaped enlargement 24. Thus arranged, the said protuberance and said enlargement act 110 as centering cones for the hinge members within the branches of the bifurcated support, and are well adapted to take up the wear of the journaled elements. 115

External threads are formed around both 120 ends of the pivot-screw 25, one of which, designated by the numeral 26 receives a nut 27, which is permanently secured to it; for instance by upsetting or riveting that end of the screw over the nut, as at 28. Fastened in this manner, the nut serves as a supplementary head to the screw, and abuts on the underside against the outer face of the annulus 21 at the lower end of the adjoining branch of the support 19, thereby prevent- 125 130

ing any advance of the screw beyond the set limit. The thread at the other end of the screw, indicated by the numeral 29, is intended to receive a nut 30, that may be 5 tightened up against the annulus 20 depending from the opposite branch of the support 19, so as to force the protuberance 22 inwardly into engagement with the concavity in the bearing 14, thereto appertaining. 10 This is done when first assembling the parts of the joint, and subsequently to re-adjust the same. Both the nuts 27 and 30 are provided with lateral slots, notches, or recesses, as at 31, to permit the application thereto of 15 a wrench or key when they are screwed over their respective extremities of the pivot screw.

While a certain preferred embodiment of this instrument joint has been shown and 20 described, it will be understood that changes in the form, arrangements, sizes, proportions and details thereof may be made without departing from the scope of the invention as defined by the appended claims.

25 Having described my invention what I desire to secure by Letters Patent and claim is:—

1. An instrument of the nature set forth, comprising hinge members bent circularly 30 upon themselves to form loops, bearing elements seated therein, and a support including means for pivotally sustaining said members from opposite sides of the same.

2. An instrument of the nature set forth, 35 including a pair of hinge members formed with opposite loops adapted for superimposition one upon the other, alined bearing elements seated in said loops, a support arranged to sustain said members, and pivotal means centering the latter from said elements.

3. An instrument of the nature set forth, comprising duplicate hinge members provided at one end with relatively thin loops 45 adapted to be joined together by inversion, bearing elements seated in said loops, a support having a branch arranged to sustain said members, and pivoting means including abutments centering the latter with regard 50 to said branch from opposite sides of said elements.

4. An instrument of the nature set forth including hinge members formed with loops adapted to be joined together, bearing elements alined in said loops, a bifurcated support the branches whereof are arranged to straddle said members, and pivoting means with abutments centering the latter within 55 said branches from opposite sides of said elements.

5. An instrument of the nature set forth comprising hinge members having loops superimposed one upon the other, alined bearing elements seated in said loops, a 60 bifurcated support straddling said members,

one branch of said support being formed with an inwardly projecting protuberance fitted in one of said elements, and a pivot with an enlargement engaging the other one of the bearing elements from the opposite 70 branch of the support.

6. An instrument of the nature set forth comprising hinge members with loops facing each other, bearings therein having alined openings with outwardly flaring concavities 75 on opposite sides of said members, a bifurcated support straddling the latter, a projection from one branch of said support engaging the concavity in one of said bearings, and a pivot with an enlargement positioned 80 to enter the concavity in the other one of the bearings adjacent to the opposite branch of the support, said pivot passing through said alined concavities and openings.

7. An instrument of the nature set forth 85 comprising superposed hinge members with loops facing each other, oppositely located bearings in said loops, a bifurcated support the branches whereof extend past the outer faces of said bearings, an integral protuberance entering one of the latter from one of said branches, a pivot threaded into the other one of the branches and having an enlargement received in the opposite bearing, and means for holding said pivot exteriorly 90 on the branch of the support carrying said protuberance.

8. An instrument of the nature set forth comprising hinge members having loops contacting laterally one with the other, bearings alined in said loops, a bifurcated support straddling the hinge end of said members, one branch of said support having an inwardly extending protuberance arranged to project into one of said bearings, the other 100 branch of the support being provided opposite the other one of the bearings with an internally threaded opening, and a correspondingly threaded element projecting from said opening so as to afford a pivotal 105 connection between both bearings and said branches.

9. An instrument of the nature set forth comprising hinge members having opposed loops formed with contacting surfaces, bearings seated in said loops, a bifurcated support the branches whereof terminate in annuli respectively positioned opposite the outer faces of said bearings, one annulus having a reentrant inner edge or margin 110 adapted to engage the bearing on the adjacent side of said support, the other annulus being provided with a threaded opening, and a pivot with an enlargement engaging said opening and thence entering the side of the other bearing thereto adjoining, said pivot operatively suspending said hinge members intermediately of said annuli.

10. An instrument of the nature set forth comprising a pair of hinge members formed 115

with end loops adapted for superimposition one upon the other, bearing elements seated apart within said loops, a bifurcated support straddling the hinge end of said members, the branches of said support terminating in annuli located exteriorly opposite said elements, one of the latter being engaged by a protuberance from the inner edge or margin of the adjacent annulus, the other 10 annulus having a threaded opening, a pivot with an intermediate enlargement engaging said opening opposite the bearing element proximate thereto and passing at the ends through both of said branches, a fastening 15 means for the end of said pivot adjoining said enlargement, and similar means adjustably retaining the other end of the pivot.

11. An instrument of the nature set forth, including a pair of hinge members having 20 each a reduced portion near one terminal thereof bent circularly upon itself to form a

loop, the looped portions of said members being arranged for superimposition one upon the other, bearing elements seated oppositely within the loops of said portions, and means 25 for pivotally connecting the members together through said elements.

12. An instrument of the nature set forth, including a pair of hinge members having oppositely disposed portions of reduced width bent circularly upon themselves to form superimposed loops, a terminal of each member adjacent to one end of the reduced portion thereof being shaped to correspond with the side of the member adjoining the other end of said reduced portion, aligned bearing elements seated within said loops, and pivotal means passing through said elements operatively connecting the hinge members together.

JOHN A. HAGERSTROM.
